R. P. HEMMING.

RUG.

No. 16,164.

Patented July 14, 1885.

A

UNITED STATES PATENT OFFICE.

RICHARD PAUL HEMMING, OF PHILADELPHIA, PENNSYLVANIA, ASSIGNOR
TO GEORGE W. ENNIS & CO., OF SAME PLACE.

DESIGN FOR A RUG.

SPECIFICATION forming part of Design No. 16,164, dated July 14, 1885.

Application filed June 1, 1885. Term of patent 3½ years.

To all whom it may concern:

Be it known that I, RICHARD PAUL HEMMING, a citizen of the United States, residing at Philadelphia, in the county of Philadelphia and State of Pennsylvania, have invented and produced a new and original Design for a Rug; and I do hereby declare that the photographic print accompanying this specification conveys to any one skilled in the art a clear understanding of the same, and is sufficient to enable such person to use my invention.

The leading features of my design consist in a triple-panel center, the middle panel showing a floral design, the end panels a ground in mosaic, with a flower in the center and a half-flower at each end. The end panels are surrounded by a narrow border or molding. The three panels are surrounded by a wide border showing a ground in mosaic, and a narrow outer border representing an ornamental molding. At each corner of the rug,

connecting the outer ornamental moldings, is shown a representation of a band—the whole as shown in the photographic print accompanying this specification.

25

The photographic print illustrates and represents one half of the design or rug. The other half, described but not shown, is exactly like it.

What I claim as my invention is—

The design for a rug, consisting of a triple-panel center, the center panel represented by conventional florid ornamentations, the end panels a floral ornamentation on a mosaic ground, surrounded by a broad border showing a mosaic ground, with cross-bands at each corner, the whole surrounded by a narrow ornamental border, as shown and described.

R. PAUL HEMMING.
